SURTAX REGISTERING AND TOTALIZING
COUNTER FOR TELEPHONY SYSTEMS

Rolf Fässer, Geneva, Switzerland, assignor to
Sodeco Societe des Compteurs de Geneve,
Geneva, Switzerland, a firm of Switzerland

Application February 1, 1950, Serial No. 141,644
In Switzerland February 2, 1949

5 Claims. (Cl. 235—92)

1

In most countries, the telephonic fee for the subscriber includes, in addition to the official fee, a so-called surtax.

The official telephonic fee is usually determined according to the duration of the call as well as to the taxation-area in which said call was established; it is then carried over the charge indicating device by means of a number of tax-impulses corresponding to the amount of the telephonic fee.

The surtax paid per telephonic call is usually graded with respect to the taxation-zone in which the call was brought about. In Switzerland, for instance, for the urban and suburban traffic, this surtax amount to 10 centimes, for trunk connections to 20 centimes. Urban call is characterised by one tax-impulse, suburban call by two impulses and trunk call by at least three impulses.

By such graded surtaxes, for the total sum of the single surtaxes to be taken during a certain period, there is obviously neither a direct relation to the sum of the impulses registered in that duration nor in respect of the number of telephone-calls achieved during the same period. Thus the subscriber of a telephone-station is not able to check the surtaxes taken by his staff during a given period.

In order to overcome this drawback of the lacking check, the following described charge indicating device for a telephonic plant including a plurality of graded surtaxes, is provided, according to the present invention with surtax-indicating means and a surtax-totalizing counter. The number of the counted tax impulses for the calling-fee is used for determining the surtax to be taken, whereby the rotation angle of the first digits drum of the charges-totalizing counter during the beginning impulses of each call, the number of which determines the surtax to be paid, is directly or by intercalation of one or several carrying wheels, conveyed by means of a leading stud onto an indicating flap rotatably mounted on a fixed axis, and onto a selecting sector; said indicating flap directly showing the surtax and said selecting sector being adapted to count the number of unities to be added in the surtaxes totalising counter.

With reference to the appended drawing, the single figure represents an embodiment of the invention. The members which do not belong to the surtax device are not shown to facilitate the understanding of their working.

The tax-impulses come into the winding 1 of the step-by-step controlling mechanism 2, 55

2

which by means of ratchet 3, drives the ratchet-wheel 4 in the direction of arrow 5. The ratchet-wheel 4 is connected to the sun wheel of the cycloidal gear system over the spindle 6. The cycloidal gear system (differential) and its adjoining reverse and locking wheels are diagrammatically shown. One sun gear of the differential mechanism is used to drive forwardly over the gear 8 the digits drum 9, in the direction of the arrow 10 a given quantity per impulse. The other sun gear of the differential is connected to the first digits drum 11 of the charge totalizing counter 12. During conversation, i. e. on receiving the tax-impulses, said second sun gear and thus the whole charge totalizing counter 12 is locked.

The digits drum 9 is subjected to the action of a spring 13, which operates against the direction of the arrow 10. Said spring is thus wound up by the action of the impulses. The zero position of digits drum 9 is located by the stud 14 co-operating with thrust 15.

The thrust or bolt 16 also moves in unison with drum 9 in the direction of arrow 10. The surtax-indicating flap 20 is stopped in the zero position by means of the arm 17 and bolt 16. Besides, an arm 37 is locked through the pawl 60, which is rotatably mounted on the spindle 61. At the first impulse, the armature 62 of the step-by-step controlling mechanism 2 acts on the pawl 60 in such a way that arm 37 becomes free. The arm 17 is then able to follow the movement of bolt 16 against which it is pressed by spring 18.

Thereby, the spindle 19 and, in unison with it, the surtax-indicating flap 20 revolves in the direction of the arrow 26. This flap is then moved, for instance, up to 10 centimes, for one impulse (urban call), also up to 10 centimes for two impulses (suburban call) and to 20 centimes for three and more impulses (trunk connections).

The thrust 21 prevents the surtax-indicating flap 20 from being further carried along after the third impulse, so that on each further impulse, the spindle 19 remains still and bolt 16 moves away from arm 17.

The driving of this surtax-indicating device is characterised by the feature that it does not moreover load the controlling magnet 1; but on the contrary, it facilitates the action thereof during the three first impulses, whereby spring 18 acts upon the digits drum 9, against the spring 13, over the arm 17.

The return to zero and the totalizing of the surtax is achieved through the releasing push-

button 22 in co-operation with a snap device. By actuation of the releasing push-button 22 in the direction of arrow 35, the lever 23 is displaced whereby the springs 24 and 28 are tensioned, because the reciprocating lever 25 is temporarily held back through the latching lever 27. The reciprocal control lever 29 also remains motionless for its lug 30 is pressed against the nose 31.

On pushing the releasing button 22 until the edge 32 runs against the bars 33, the latching lever 27 is rotated about the axis 34 and thus releases the lever 25. This latter is then pushed in the direction of the arrow 35 through the previously compressed spring 24 and the lateral extension 36 thereof brings the arm 37 back again, whereby the surtax-indicating flap 20 is returned to zero. In that position, the arm 37 is locked through pawl 60, so that the spindle 19 is stopped and cannot hinder the return to zero of the digits drum 9, by the arm 17.

Owing to the movement of the lever 25 in the direction of the arrow 35, the lug 30 is also released, whereby the lever 29 is shifted in the same direction and its end 38 engages itself at once into a notch 44 or 46 of the selecting sector 39, before the same is moved and can return to zero in unison with the spindle 19.

When the reciprocal lever 29 is shifted in the direction of the arrow 35, its finger 40 is pressed against the stud 41 and thus rotates the lever 42 around the axis 43. If the end portion 38 has engaged itself into one of the notches 44, then the ratchet 45 moves backwards one tooth (local and suburban traffic); but if said end portion 38 has engaged itself into the notch 46 (trunk connections), then the ratchet 45 moves backwards two teeth.

During its movement in the direction of the arrow 35, the lever 25, on acting over a locking gear of the differential mechanism 7 (not shown), releases the charge-totalizing counter 12, so that the spring 13 brings the digits drum 9 back to zero, in a direction opposite to the arrow 10, whereby the stud 14 runs against the thrust 15. The gearing ratios of the differential mechanism are selected in such a way that, on the returning movement of the digits drum 9, the charge totalizing counter 12 forwardly revolves by the same amount. As soon as the stud 14 is stopped through said thrust 15, the charge totalizing counter 12 is locked again, through known means which are not described in the present specification, until next return to zero of the digits drum 9.

When the operator releases knob 22, reciprocating levers 23, 25 and 29 are drawn back again through spring 47 and the latching lever 27 locks lever 25 so that the snap device takes its starting position again.

By the backward motion of lever 29, the finger 40 thereof released the lever 42, which latter, being henceforth drawn through the spring 48, turns the ratchet wheel 49 one or two teeth forward in the direction of arrow 50. Through this action, spindle 43 together with digits drum 51 of the surtax-totalizing counter 52 are given a further rotary motion by one or two figures.

After end part 38, on its back movement, has moved away from the corresponding notch 44 or 46, the selecting sector 39 is released, on its turn, and is returned back into the zero position against the pin 54, through the action of spring 53.

The abrupt movement of lever 25 in the direction of arrow 35, after depression of the releasing

knob 22, is required in order that all operations, which are prepared or released through said lever 25, should be almost simultaneously and automatically performed. It thus becomes impossible by inadvertently handling the knob 22, to only partially reset the mechanism. Under these conditions, possible falsification such as a double or more addings of the surtax into the totalizing counter, are left out.

The hereinbefore described apparatus is only a possible embodiment of the invention. By suitably forming the indicating flap 20, by a displacement of thrust 21 as well as by a corresponding realization of the selecting sector 39, the amount of the surtax to be paid can be modified at will.

What I claim is:

1. In a telephonic fee indicating device for telephonic plants subject to a plurality of surtaxes, including a charges totalizing counter (11—12) provided with digit drums and adapted to be forwardly driven, step by step, by a controlling mechanism provided with an electromagnet receiving a number of current impulses corresponding to the various areas of traffic (local, suburban or trunk connections), whereby the number of current impulses for each calling selectively determine the amount of the various surtaxes for said traffic areas, in combination: a charge indicating digit drum (9) connected to the controlling mechanism so as to be rotated by the same only in the direction of the increasing charges, a spindle (19) carrying a surtax-indicating flap (20) and a coupling arm (17), a stationary stop in the path of said flap, means for exerting an eccentric thrust on the charge indicating drum, said coupling arm being biased against the eccentric thrust in the same direction of rotation as that imparted thereto through the action of the controlling mechanism, a driving member (54) and a reset arm (37) on said spindle, a surtax selecting member (39) adapted to be positively rotated by said driving member (54) in one direction, a spring (53) for urging said selecting member in a reverse direction of rotation, said selecting member having a plurality of stepped abutment surfaces (44—46), each representing the amounts of the successive surtaxes to be registered, a spring urged releasing knob (22), a snap acting mechanism adapted to be put in operation by said knob and comprising reciprocal means (29—38), having motion limiting means cooperating with said abutment surfaces, a surtax totalizing counter (51—52); unidirectional variable stroke actuating means for said totalizer (42, 45, 48, 49) inserted between the reciprocal means and the surtax totalizing counter, said reciprocal means being adapted to cooperate with said abutment surfaces by one of the strokes of said releasing knob and also to have the surtax amount added in the surtax totalizing counter, by the other strokes of said knob, said snap acting mechanism including a resetting member (36) adapted to drive said reset arm (37) for returning the surtax indicating flap to zero by a snap released operation.

2. A telephonic fee indicating device as defined in claim 1, said surtax selecting member comprising a notched sector loosely mounted on said spindle, said driving member being fixed to said spindle and said spring constantly urging said sector against the driving member on said spindle, in order to reset the notched sector to zero, when the cooperation between the said reciprocal means (29—38) and the notches of said sector has ceased.

3. In a telephone feed indicating device for telephonic plants subject to a plurality of surtaxes, including a charges totalizing counter (11—12) provided with digit drums and adapted to be forwardly driven, step by step, by a controlling mechanism provided with an electromagnet receiving a number of current impulses corresponding to the various areas of traffic (local, suburban or trunk connections), whereby the number of current impulses for each calling selectively determine the amount of the various surtaxes for said traffic areas, in combination: a charge indicating digit drum (9) having a winding spring (13), a differential mechanism (7—8) having a locking gear therein connected to said charge indicating drum and to said charges totalizing counter, so that the charge indicating digit drum can be driven by the differential mechanism only in the direction of the increasing charges against the action of said winding spring, a spindle (19) carrying a surtax-indicating flap (20) and a coupling arm (17), a stationary stop in the path of said flap, means for exerting an eccentric thrust on the charge indicating drum, said coupling arm being biased, a weight against the eccentric thrust in the same direction of rotation as that imparted thereto through the action of the differential mechanism, a reset arm (31) on said spindle, a backward spring urged releasing knob (22—47); a reciprocalable cam (32) adapted to be operated by said releasing knob, a snap releasing lever (27) having a part (33) normally located in the path of said cam, a snap controlling spring (24) adapted to be tightened by the depression of the releasing knob, a resetting device (25—36), a part of which is normally inserted between one edge of said releasing lever and said snap controlling spring, whereby a member (36) of said resetting device is adapted to rotate said reset arm (37) together with said surtax indicating flap to the zero position by the action of said snap controlling spring (24), caused by the cam (32) raising said snap releasing lever (27), said resetting device including means for removing said locking gear to disconnect said charge indicating digit drum from charge-totalizing counter, so that said winding spring (13) brings the charge indicating drum to zero.

4. In a telephonic fee indicating device of the class referred to, comprising a charge totalizing counter adapted to be driven step by step, by an electromagnet controlling mechanism, according to a number of current impulses corresponding to the different traffic areas, whereby the number of current impulses for each calling selectively determine the amount of the various surtaxes for said traffic areas, in combination: a charge indicating digit drum provided with a winding spring adapted to return said drum to zero, said charge indicating drum being adapted to be positively rotated from the charges totalizing counter, a spindle carrying a first arm provided with a surtax indicating flap, and a coupling arm, a set of all the figures used for the various surtaxes on said flap, a stationary stop in the path of said first arm spaced from the zero position thereof at an angle equal to the angle taken by the whole set of figures on said flap, means (14—15) for stopping said charge indicating drum in its zero position, means for exerting an eccentric thrust on the charge indicating drum, said coupling arm being biased against the eccentric thrust in the same direction of rotation as that imparted to said charge indicating drum through the action of the charge totalizing counter, a surtax select-

ing sector loosely mounted on said spindle and formed with as many peripheral notches as the figures on said surtax indicating flap, the depths of said notches corresponding to the various or same amounts of surtaxes, a driving member (54) on said spindle for positively rotating said surtax sector in the direction of the increasing surtaxes, a spring (53) adapted to urge the surtax sector in a reverse direction of rotation to reset the same to zero position; a spring urged releasing knob; a snap acting mechanism operated by said knob and comprising reciprocalable control means, a surtax totalizing counter, unidirectional variable stroke actuating means for said totalizer inserted between said reciprocalable control means and said surtax totalizing counter, said control means engaging with said notches by the depression stroke of the releasing knob, and to have the surtax amount added in said surtax totalizing counter through said unidirectional variable stroke actuating means in the back stroke of said knob, means (36) inserted between the snap-acting mechanism and the flap carrying spindle for returning the indicating flap to zero by a snap released operation.

5. In a telephonic fee indicating device for telephonic plants subject to a plurality of surtaxes, including a charges totalizing counter (11—12) provided with digit drums and adapted to be forwardly driven, step by step, by a controlling mechanism provided with an electromagnet receiving a number of current impulses corresponding to the various areas of traffic (local, suburban or trunk connections), whereby the number of current impulses for each calling selectively determine the amount of the various surtaxes for said traffic areas, in combination: a charge indicating digit drum connected to said controlling mechanism to be rotated by the latter only in the direction of the increasing charges, a spindle carrying a surtax indicating flap and a coupling arm, a set of figures on said flap corresponding to the whole succession of the surtaxes, a stationary stop in the path of said flap, spaced from the zero position thereof at an angle equal to the angle taken by the entire set of figures on said surtax indicating flap, means for stopping said charges indicating drum in its zero position; means for exerting an eccentric thrust on the charge indicating drum, said coupling arm biased against said eccentric thrust in the direction of rotation imparted thereto through the controlling mechanism, a driving member (54) and a reset arm on said spindle, a surtax selecting sector adapted to be positively rotated by said driving member in one direction, a spring for urging said surtax selecting sector in a reverse direction of rotation, said surtax selecting sector having a number of peripheral notches equal to the total number of surtaxes, the depths of said notches corresponding to the various or same amounts of the surtaxes to be registered, a spring urged slideable releasing knob, a snap acting mechanism disposed on the sliding path of said releasing knob and comprising a resetting member (36) to drive said reset arm (37) by a snap released operation, a surtax totalizing counter (51—52) connected to a ratchet wheel (49), a pawl (45) and a control spring (48) adapted to drive said pawl and said ratchet wheel, reciprocalable surtax transferring means comprising a strip (38) adapted to engage itself by snap action into a notch of said surtax selecting sector on the depression of said releasing knob, and a finger (40) to withdraw said pawl with respect to said ratchet wheel.

a distance corresponding to the depth of the notch actually reached by said strip, whereby, on the back stroke of said releasing knob, said control spring (48) drives said ratchet wheel and surtax totalizing counter so that the latter registers the surtax selected by said selecting sector.
